LIGHT SWITCH ACTUATOR

James C. Corbett, Salt Lake City, Utah, assignor to
Bonnie L. Bricker, Bountiful, Utah

Filed Nov. 13, 1970, Ser. No. 25,954

Term of patent 14 years

Int. Cl. D8—08

U.S. Cl. D8—183

FIG. 1

FIG. 2

FIG. 3

FIG. 4

FIG. 5

FIG. 1 is a front elevation of a light switch actuator showing my design.

FIG. 2 is an elevation of the left edge;

FIG. 3 is an elevation of the right edge;

FIG. 4 is an edge view of the top; and

FIG. 5 is an edge view of the bottom.

The rear of the actuator is flat and unornamented.

I claim:

The ornamental design for a light switch actuator, substantially as shown and described.
